Patent Drawing of a fountain pen showing a longitudinal section of the pen body and a side view of the forward portion of the pen. The drawing illustrates the internal structure of the pen, including the ink container, reservoir, and pen point.

UNITED STATES PATENT OFFICE

2,269,232

PEN

Frank A. Schreiner, Chicago, Ill.

Application May 26, 1941, Serial No. 395,261

5 Claims. (Cl. 120—42)

This invention relates to a pen and more particularly to a fountain pen provided with an ink concentrate, a reservoir for water, and constructed to supply water to the ink concentrate as needed for writing.

Pens have been prepared heretofore which have been designed to be filled with water and to operate under such conditions on an ink concentrate. The previous pens have been so constructed that the passageways quickly became clogged and the concentrate no longer available. The present pen is so constructed that ink is made only as required for writing and no substantial quantity of unused ink, as distinguished from ink concentrate, ever remains in the pen.

The invention is illustrated in the drawing in which Figure 1 is a plan view of the pen; Figure 2 is a side view of the forward portion of the pen; Figure 3 is a bottom view of the same portion; Figure 4 is a fragmentary longitudinal section of the pen; Figure 5 is a transverse section taken along the line 5—5 of Figure 4; and Figure 6 is a fragmentary plan view of the ink concentrate container.

As shown in the drawing, the pen comprises a body 10 provided with an open neck within which is mounted a feed member 11 provided with a channel 12 which has longitudinal fissures 27. Within the body any suitable liquid container means, such as a rubber sack 13, is provided. The feed member is provided with a narrower rearward extension 14 to which the end of the sack 13 is secured.

The feed member has an elongated forward extension 15 which closely engages the pen point 16 and the nose 17 of which extends nearly to the tip 18 of the pen point. An opening 28 may be provided near the front end of the feed member. The pen point 16 is made of the usual flexible metal and is provided with the customary slit 20 dividing the end of the pen point and extending rearwardly to the opening 19. The channel 12 of the feed member extends from the reservoir provided by the sack 13 up to and over the opening 19 and over a substantial portion of the slit 20.

The feed member 11 is annular in form and centrally located therein is an ink container 21 of any suitable material but preferably of a suitable plastic unaffected by ink such as pyralin or the like. This ink container is filled with a suitable ink concentrate or powder 22. It is closed at its rear end by any suitable form of plug 23 and is provided at the top with a longi-

tudinal narrow slot 24 extending from the front of the container or cartridge a substantial distance to the rear. The dimensions and location of the slot 24 are of considerable importance. 5 As will be noted, the ink container and accordingly the slot are located on the opposite side of the pen point from the channel 12 so that water can pass into the ink only after passing through the small opening 19 in the pen point, 10 or between the individual points of the pen when they are spread apart along the slit 20. In addition, however, the size of the opening in the ink container must be correlated to the surface tension characteristics of the container, of the ink, and of the pen point, in such manner that an excessive quantity of water will not be drawn into the ink container by surface tension or capillarity. If the slot 24 is too wide, water will be drawn into the container by the ink and an 15 undesirable large quantity of liquid ink will be manufactured during writing. On drying, this ink will clog the opening 12. By making the opening smaller, it has been found that clogging does not occur. For ordinary purposes with the 20 usual pen point materials, the usual ink powder, and a plastic material such as pyralin as the container for the ink, the slot should not be more than 0.007 inch across and it is preferred to make it approximately 0.005 inch across. In general 25 the slot should not be less than 0.003 inch across on the average. It should be understood that these dimensions are for a continuous elongated slot and, if it is desired to have disconnected rounder openings, the dimensions may be somewhat increased. It is preferred, however, to use 30 a single continuous slot of the dimensions mentioned.

In using the pen container 21 is filled with powdered ink 22 and is placed in the assembly. 35 The reservoir is then filled with water 26 in the usual manner as, for example, by a lever mechanism 25, after which the pen is employed for writing in the usual manner. When the tip 18 of the pen is pressed upon the writing surface the two ends of the pen are spread, causing the slit 20 to widen. This widening draws water from the channel 12 and the opening 19 into the 40 slit 20 and causes it to engage the walls of the slot 24. Under these conditions it picks up sufficient ink powder from the container to form a suitable writing ink which is immediately supplied to the end of the pen. The ink container 21, when made of a size to fit readily within a pen of ordinary dimensions, will hold enough 45 ink concentrate to make approximately 8 oz. of 50 ink.

fluid ink and, therefore, a single container will furnish the ink supply of many months for the ordinary individual and, in many cases, will provide for several years use of ink.

When the cartridge has been exhausted it may be replaced readily, but the whole mechanism is so inexpensive that it can be manufactured and sold at retail for less than the cost of 8 oz. of good fluid ink and, therefore, in many cases the entire assembly can be discarded when the ink has become exhausted. For this reason it is quite suitable to employ a stainless steel pen point furnished with a tip of suitable non-corrosive metal such as the so called "iridium." These points have an effective life corresponding in general to the ink supply of the pen.

It will be understood of course that the feed member 11 and the cartridge 21 effectively close the neck of the body of the pen, and that the cartridge 21 effectively seals the water within the sack 13 except for the improvement thereof through the channel 12 as indicated. If desired, the feed member may be made as a unit to replace the feed member in any standard pen. In such case it would generally be made somewhat smaller and provided with suitable interlock means such as screw threads.

The foregoing detailed description has been given for clearness of understanding only, and no unnecessary limitations should be understood therefrom.

What I claim as new, and desire to secure by Letters Patent, is:

5 1. A pen assembly comprising a slit pen point, means for feeding water to one surface of the pen point adjacent the slit, and an ink cartridge on the other side of the pen point, the cartridge being provided with a narrow opening overlapping the slit.

10 2. A pen assembly as set forth in claim 1, in which the opening in the container is an elongated longitudinal slot sufficiently narrow to prevent substantial absorption of water by the ink in the container and wide enough to furnish ink to the pen.

15 3. A pen assembly comprising a slit pen point, means for feeding water to one surface of the pen point adjacent the slit, and an ink cartridge on the other side of the pen point, the cartridge being provided with a narrow elongated slot overlapping the slit in the pen point, the width of the slot being not substantially less than 0.003 inch and not substantially more than 0.007 inch.

20 4. A slotted pen point comprising a body portion, a water reservoir, a pen point, a container, an ink concentrate within the container, means for supplying water from the reservoir to the upper surface of the pen point, and an opening in the container for the ink concentrate on the opposite side of the pen point.

25 5. A pen as set forth in claim 4, in which the opening in the ink concentrate container is a narrow elongated slot overlapping the slit in the pen point.
